UNITED STATES PATENT OFFICE.

SIEGFRIED HELD, OF CHICAGO, ILLINOIS.

APPARATUS FOR PRODUCING OZONE.

1,038,130.

Specification of Letters Patent. Patented Sept. 10, 1912.

Application filed August 2, 1911. Serial No. 641,909.

To all whom it may concern:

Be it known that I, SIEGFRIED HELD, a subject of the Emperor of Austria-Hungary, residing at Chicago, in the county of Cook and State of Illinois, have invented certain new and useful Improvements in Apparatus for Producing Ozone, of which the following is a specification.

This invention relates to an improved electrical apparatus for the production of ozone, and it consists in certain peculiarities of the construction, novel arrangement, and operation of the various parts thereof as will be hereinafter more fully set forth and specifically claimed.

One of the objects of my present invention is to furnish a compact and portable apparatus for the production of ozone, which shall be of such construction that the currents of ozonized air can be directed as desired, by a slight change in the position of the apparatus, and which shall be simple and inexpensive in construction, strong, durable, and readily attached to any suitable source of electric supply for furnishing current of the required tension to the electrodes.

Another important object, is, to provide improvements in the construction of the electrodes, as well as, in the means for their support and novel arrangement, whereby the efficiency of the apparatus will be augmented, and the deterioration of the electrodes, through oxidation, lessened, and besides, the formation of objectionable gases, such as nitrous oxid, prevented or reduced to a minimum.

A further object is to provide simple and efficient means for holding the walls of the electrodes apart in parallelism with one another, and one within the other, yet in such a manner, as to permit of the entire surface of one of them being exposed to the current of air as it is forced between said electrodes.

Other objects and advantages of the invention will be disclosed in the subjoined description and explanation.

As the present invention relates particularly to the construction, arrangement and mounting or support of the electrodes and their connecting parts, I have shown said parts only in detail, and will hereinafter particularly describe the same, referring to the other parts of the apparatus in a general way only, it being deemed unnecessary to either show or describe the last mentioned

parts in detail, as they may be of the ordinary or any preferred construction and their operation is well known.

In order to enable others skilled in the art to which the invention pertains, to make and use the same, I will now proceed to describe it referring to the accompanying drawings in which—

Figure 1, is a view partly in section and partly in elevation of an apparatus for producing ozone, embodying the invention. Fig. 2, is a view of the inlet end of the drum in which the electrodes are mounted showing a portion of the supporting arm for said drum, Fig. 3, is an end view of the opposite or discharging end of the drum showing the electrodes mounted therein and illustrating a portion of the arm which supports said drum, and Fig. 4, is an enlarged perspective view of a portion of the outer electrode showing means thereon for holding pieces used for supporting said electrode on the envelop or closure of the other electrode.

Corresponding numerals of reference refer to like parts throughout the different views of the drawings.

The reference numeral 7, designates a casing which may be of any suitable size, form, and material, within which is located a transformer 8, of the ordinary or any preferred construction, which is electrically connected to a motor or rotary converter, 9, as the case may be, in the usual manner by means of leads or conductors 10, and 11. As shown, the motor or rotary converter 9, is mounted on the top of the casing 7, and may have electrical connection through leaders or conductors 12, and 13, with a suitable source of electrical supply, not shown. Mounted on the shaft of the motor or rotary converter is a fan 14, which is driven thereby and is used to force currents of air through a drum 15, and between the electrodes, which drum is mounted on a hollow arm 16, extended horizontally and then upwardly from the casing 8, of the apparatus. The drum 15, is horizontally supported on the arm 16, and has at its end adjacent to the fan 14, a flared portion 17, to receive and conduct the currents of air furnished by the fan, through the drum. Located in the drum 15, at about the juncture thereof with the flared portion 17, is a spider-frame 18, which is preferably made of fiber, and is fitted snugly in the drum, and may be held

therein by frictional contact therewith, or otherwise. The central portion of the spider-frame 18, is provided with a disk or member 19, from which are extended radially arms 20, which are united by a circular portion or ring 21, which is likewise united by means of arms 22, to the outer portion or ring 23, of said frame, which latter ring or outer portion is fitted snugly in the drum 15, as before stated. Secured to the inner surface of the disk or member 19, of said spider-frame is a metal socket 24, which is in contact with a binding post 25, to which one end of a conductor 26, is connected, which conductor is extended through the hollow arm 16, into the casing 7, and electrically connected to the transformer. The socket 24, is preferably internally screw-threaded to engage an externally screw-threaded sleeve 27, which is secured on one end of a glass bulb or closure 28, which is extended horizontally within the central portion of the drum 15, and projects at its free end, to near the discharging end of the drum.

As is clearly shown in Fig. 1, of the drawings, the bulb or closure 28, which may be made of any suitable material, but preferably of glass, has its rear end, or that end thereof adjacent to the spider-frame 18, reduced, and is provided near its other end with a series of inwardly extended projections 29, which projections are preferably made by indenting the bulb or closure 28, on its outer surface, thus forming corresponding projections on its inner surface. Located within the bulb or closure 28, is a metal stem 30, which is secured at one of its ends so as to contact with the socket 24, thus forming electrical connection through said socket and the binding post 25, with the conductor 26, and transformer. At its inner end, the metallic stem 30, is provided with two forwardly disposed metal arms 31, and 32, which, as is clearly shown in Fig. 1, of the drawings, extend in opposite directions from the stem 30, and then forwardly in parallelism with one another. Mounted on the arms 31, and 32, and encompassing a portion of the stem 30, is a tubular electrode 33, which is preferably made of aluminum, and is supported on the stem 30, by means of the arms 31, and 32, which are disposed diametrically opposite each other, within and against the inner surface of the front portion of the electrode 33, as will be clearly understood by reference to Fig. 1, of the drawing. When thus mounted, the front end of the electrode 33, will rest against the projections 29, of the bulb or closure 28, thus holding the main part of the electrode 33, at a slight distance from the bulb or closure, which said electrode is preferably sealed in vacuum within said bulb. Located in the front or discharging portion of the drum 15, is another spider-

frame 34, which includes two concentric rings 35, and 36, united by radially disposed arms or portions 37, which afford spaces for the passage of air. The inner ring 35, is provided on its inner surface 70 with a series of inwardly extended projections 38, which are used to rest against the front portion of the bulb or closure 28, so as to assist in supporting the same within the drum. Surrounding the bulb or closure 28, 75 is another electrode 39, which is preferably made of aluminum and is electrically connected by means of a conductor 40, with the transformer, which conductor is extended through the hollow arm 16, and into the 80 casing 7, which incloses said transformer. The electrode 39, is provided at each of its ends with a series of inwardly extended lips 41, which are arranged in pairs, and are preferably formed by being punched 85 out of the material of which said electrode is made. Inserted between each pair of the lips 41, is a distancing piece 42, of fiber or other insulating material, which pieces contact with the outer surface of the bulb or 90 closure 28, so as to hold the electrode 39, at a slight distance therefrom, yet in parallelism with the same as well as with the electrode 33, which as before stated, is inclosed by said bulb.

From the foregoing and by reference to the drawings, it will be readily understood and clearly seen, that when the apparatus is operatively connected, to a suitable source of electrical supply, the fan or blower 14, 100 will be rotated, thus causing currents of air to be forced through the drum 15, and between the electrode 39, and the bulb or closure 28, for the electrode 33, which air will be accordingly ozonized and discharged 105 at the outlet or discharging end of the drum:

Having thus fully described my invention what I claim as new and desire to secure by Letters-Patent is—

1. An apparatus for producing ozone, 110 comprising a source of current, a vacuum tube having on its inner surface near one of its ends a series of projections, a tubular electrode located in said tube and resting at one of its ends on said projections, a 11 tubular electrode surrounding the vacuum tube and the first named electrode, means interposed between the outer electrode and said tube for maintaining them parallel and spaced apart, current conveying connections 12 to said electrodes, and means for passing air along the exterior of said tube in the direction of the length thereof.

2. An apparatus for producing ozone comprising a source of current, a vacuum 12 tube, a tubular electrode located in said tube, another tubular electrode surrounding said vacuum tube and the first named electrode and having at each of its ends a series of in-turned lips arranged in pairs, an insulating 13

piece located between each pair of said lips and resting on the outer surface of the vacuum tube, current conveying connections to said electrodes, and means for passing 5 air through the space between the outer electrode and said closure.

3. An apparatus for producing ozone, comprising a source of current, a vacuum tube having on its inner surface near one 10 of its ends a series of projections, a tubular electrode located in said tube and resting against said projections, a tubular electrode surrounding the vacuum tube and the first named electrode and having at each of 15 its ends a series of inturned lips arranged in pairs, an insulating piece located between each pair of said lips and resting on the outer surface of the vacuum tube, current conveying connections to said electrodes, 20 and means for passing air through the space between the outer electrode and the tube.

4. In an apparatus for producing ozone, the combination with a casing having an arm extended therefrom, of a drum mounted 25 on said arm, a vacuum tube supported within the drum and insulated therefrom, an electrode within said vacuum tube, a tubular electrode surrounding the vacuum tube and the first named electrode and 30 spaced from said tube, a transformer within said casing, electric connections uniting the transformer and said electrodes, a motor or rotary converter mounted on the casing, a fan mounted near one end of the

drum and driven by said motor or converter, connections leading from a source of current to the motor or converter, and connections uniting the motor or converter and the transformer. 35

5. In an apparatus for producing ozone, 40 the combination with a source of current, of a suitably supported drum, a vacuum tube mounted within the drum and insulated therefrom, a tubular electrode located in said tube, another tubular electrode surrounding the vacuum tube and the first 45 named electrode and having at each of its ends a series of inturned lips arranged in pairs, an insulating piece located between each of said lips and resting on the outer 50 surface of the vacuum tube, current conveying connections to said electrodes, an electrically driven fan mounted near one end of the drum for causing air to pass through the space between the outer electrode and 55 the vacuum tube.

6. In an apparatus for producing ozone, a tubular electrode having on one of its surfaces a series of lips formed integrally with the electrode and arranged in pairs, 60 and an insulating piece located between each pair of said lips to rest against a support from which said electrode will be held at a distance.

SIEGFRIED HELD.
